CLAIM

The ornamental design for a portion of multi-function printer, as shown and described.

DESCRIPTION

FIG. 1 is a front, top, and left side perspective view of a portion of multi-function printer showing our new design; FIG. 2 is a rear, top, and right side perspective view thereof; FIG. 3 is a front, top, and right side perspective view thereof; FIG. 4 is a front elevation view thereof; FIG. 5 is a rear elevation view thereof; FIG. 6 is a left side elevation view thereof; FIG. 7 is a right side elevation view thereof; FIG. 8 is a top plan view thereof; and, FIG. 9 is a bottom plan view thereof.
The broken lines depict parts of the portion of multi-function printer that form no part of the claimed design.
